WOOD-BURNING BROODER STOVE

Perry S. Martin, Harrisonburg, and Charles C. Turner, Broadway, Va., assignors to Shenandoah Equipment Corporation, Harrisonburg, Va.

Application November 13, 1935, Serial No. 49,638.

5 Claims. (Cl. 119—32).

This invention primarily relates to brooder stoves, having for its principal object the provision of a wood-burning stove of general utility for use where close temperature control is desirable or necessary and where absolute dependability of operation can be secured with minimum attention. An important feature of the present invention is the provision of a wood-burning stove specifically designed for brooder work in which is incorporated provision for shielding the sides of the stove from direct contact with the burning fuel while directing the heat against the upper portions of the stove which are surrounded by the hover, which latter in the present invention is placed at the top of the stove.

A further object of the invention is to provide a wood burning stove which causes the fuel to be consumed from the bottom upward, in other words our object is to confine the combustion to the bottom of the fuel bed. We thus insure a more complete combustion of the fuel by burning the considerable amount of charcoal which in stoves of the prior art was covered by the ashes falling from the consumed top wood; in the past this unburned charcoal not only represented an appreciable loss of fuel but also made it necessary to clean out the stove more often. In our device we get slow but complete combustion with much less attention.

Another object is to provide a brooder stove which does not get over hot on top and we accomplish this by placing a baffle between the top of the stove and the fire bed. This baffle also performs the function of guiding the hot gases of combustion against the sides of the stove whereby most of the heat is conducted thru the sides into the air beneath the hover and thus primarily heats the hover rather than the brooder room.

Another object is to provide a safer wood burning brooder stove and one which may be placed on the usually litter-covered floor of the brooder room and operated without danger of fire.

A still further and important object of the invention is to provide a very light and easily operable pilot damper in combination with a light main damper connected to open in graduated steps whereby the damper never opens wide enough at any time to supply air in such large quantities to permit too rapid burning of the wood. In other words we provide a temperature-controlled damper which upon call for additional heat first uncovers a small opening and if this does not yield the needed increase of warmth,

then uncovers a much larger opening. This control in cooperation with the other improved construction permits an accurate brooder temperature control for at least twenty-four hours without attention when burning almost any kind of wood, whether scrap lumber or wood from the wood-yard, in all seasons of the year.

We accomplish these and other objects of the invention by providing a stove of air tight construction and having its interior divided by a fire pot into a fire chamber and a lower air chamber, the lower chamber being supplied with air by a thermostatically controlled damper. The walls of the fire pot are spaced from the walls of the air chamber and are provided with tuyères evenly distributed about the fire pot and louvre shaped to direct air jets downwardly into the base of the burning fuel at a rate controlled by the damper at the inlet which damper is controlled in turn by a thermostat in accordance with the amount of heat radiated into the brooding zone. The interior walls of the fire box or fire chamber are provided with vertical ribs or ridges for keeping the fuel out of contact with the walls and to provide a space for the rising combustion air thus insuring a uniform burning of the fuel on all sides. Just below the outlet opening which is located centrally in the top of the fire chamber, we provide a baffle for directing the hot gases of combustion against the side walls as they travel toward the outlet.

Referring to the drawings:

Figure 1 is a perspective view of the brooder with a portion of the hover raised and showing the door open for refueling.

Figure 2 is a small scale view of the brooder in operative position.

Figure 3 is a vertical longitudinal section thru the stove and taken on line 3—3 of Figure 4.

Figure 4 is a vertical transverse section thru the stove and taken on line 4—4 of Figure 3.

Figure 5 is an enlarged detail front view of the automatic damper shown in section at the lower left corner of Fig. 4.

Figure 6 is a view taken on line 6—6 of Figure 5, and shows a central vertical section thru the damper in its closed position.

Figure 7 is a view similar to Figure 6 but showing the pilot damper open.

Figure 8, which is a view also taken on line 6—6 of Figure 5, shows both the pilot and main damper in open position.

As will be seen from the drawings the preferred embodiment of our invention consists of a box-like structure 10 of oblong form and pref-

erably but not necessarily rectangular having side walls 11 and 12, front and back walls 14 and 16 and a flat top and flat bottom 18 and 20, the latter being spaced from the floor 21. In 5 the upper part of the front wall 14 is a doorway 22 for feeding fuel to and removing ashes from the fire box 23. The fire box is supplied with combustion air which flows via the intake 24 in the lower part of side wall 11, into the air chamber 25 and then thru the openings 26 in the side walls of the fire pot 27; each opening is provided with a deflector for directing the air downward and therefore may properly be called a louvre. The top 18 which is located below the 15 top of the walls in order to provide a water reservoir, is provided with a central outlet opening 30 having a collar 31 for attaching to the usual stove pipe 32 shown in Figure 2. To the top edge 33 of the box is secured, permanently or otherwise, a downwardly and outwardly sloping hover 34 having one section 34 hinged at 35 so that it may be raised to expose the door for refueling or removing ashes.

The doorway 22 is of air tight construction 25 having a rather wide outwardly projecting frame 36 which due to its thickness not only resists warping but also prevents the sheet iron front wall 14 from warping under changes of temperature. The door proper 37, hinged at its upper 30 edge 38, is provided with reinforcing flanges 39 for telescoping over the frame 36 so that when secured shut by means of spring clamps 40 on each side of the frame the door is substantially air tight which condition is quite important if 35 any appreciable degree of control is to be obtained. It will also be noted that the hinged hover section 34 has a cutaway portion so that it may bear against the closed door at 41 to further aid in making the same air tight.

40 In order further to make the stove of air tight construction thruout the joints are all electro-welded as shown at 42 to 47 inclusive. Thus entry of air into the stove is solely thru the air inlet 24 which is under the fairly accurate control of 45 a damper mechanism 50 shown in detail in Figures 5, 6, 7 and 8. The main damper 51, pivoted at 52, normally lies flat against the outer end of the short piece of pipe 53 which tilts slightly upward in order that the weight of the damper 50 may act to keep the opening tightly closed. In 50 the main damper is a smaller aperture 54 adapted to be covered by the pilot damper 55 which is also pivoted at 52 and is provided with an ear 56 for receiving the hook 57 which is part of the 55 linkage operated by the thermostat 58. The movement of the pilot damper 55 with respect to the main damper is limited by the cotter pin 59 so that if the thermostat calls for more draft than the pilot can give then the main damper 60 begins to open. The damper construction is claimed in our co-pending divisional application Serial No. 273,982, filed May 16, 1939.

65 Referring to Figures 3 and 4 it will be seen that the fire pot 27, welded at its upper rim to the side and end walls as at 44, is spaced from said walls at 60 and 61 so that the cool incoming air flowing toward the louvre like openings 26 prevents the side walls from becoming overheated. The bottom of the fire pot is spaced from the 70 bottom 20 of the stove which in turn is spaced from the floor 21 as already mentioned, thus providing ample heat insulation between the floor and the fire pot. As will be noted in Figures 3 and 4 the louvre like openings 26 are stamped out 75 so as to direct the streams of air downwardly

into the base of the fire. These louvre like openings are distributed rather uniformly about the fire pot and are of sufficiently small cross sectional area to cause the air to flow downward in small jets thus insuring a sure and even burning 5 on all sides of the fuel. The total cross sectional area of the louvre like openings is approximately equal to that of the intake 24. The louvre like openings are located a considerable distance 10 above the floor of the fire pot so that ashes may accumulate for several days at a time before rising high enough to affect the flow of air thus providing a stove that requires no attention for days 15 at a time and during very mild weather only about once a week. 15

The side walls of the fire chamber are provided with ribs 64 which keep the wood out of contact with the walls and provide passages for the upwardly moving hot combustion gases. At the top is a dished baffle 65 which is spaced slightly 20 at its periphery from the side walls and is provided with a central opening 66 at the downwardly directed apex for permitting creosote and other condensates which drip from the smoke pipe to drain into the fuel bed. A bracket 48 25 may be placed on each side of the baffle if this is found desirable. The spacing of the baffle from the side walls and the conical shape tends to keep the hot gases in contact with the side walls 30 whereby the walls uniformly conduct a maximum amount of the generated heat out into the entire zone under the hover. The peripheral spacing of the baffle from the walls is about enough to provide an air passage approximately equal 35 to the outlet 30. The ribs and the baffle prevent the formation of the usual hot spots due to uneven burning and concentration of the hot gases as they flow toward the flue and they also cause the dissipation of a maximum amount of the heat before it enters the flue. 40

The operation of our stove is quite simple consisting in kindling a fire in the fire pot 27, then filling the fire chamber with convenient fuel of almost any description, i. e., green wood or dry wood, or any kind of blocks or pieces of wood 45 that may be found around the barn yard or wood lot. The door 37 is then closed and latched tightly by means of the spring latches 40, the hover section 34 is lowered into place. Since the stove and the brooding zone are at first relatively cold the thermostat mechanism 58 at this time will be holding the damper 50 in its wide open position but as the room and zone heat up the thermostat will permit first the main damper 51 to close and then as the zone gets warmer 55 the pilot damper is allowed to close or partly close. Then the thermostat may be regulated to maintain any desired hover temperature by adjusting the wafer screw 70 in the usual manner. 60

65 It will be appreciated in view of Figure 1 taken with the preceding description that the draft is controlled almost entirely in accordance with the temperature of the air in the brooding zone because very little heat is conducted to the wafer 71 by the supporting bracket 72 and this can be further reduced if deemed advisable by mounting the thermostat independently of the stove. Furthermore, the wafer can be screened 70 entirely from direct radiation of the stove if found necessary. By placing the hover at the highest edge of the stove almost the entire heat produced by the burning fuel is caught under the hover where it can be utilized by the chicks.

75 Altho we have described our invention as em-

bodied in a brooder stove, it is to be understood that it can be used with great advantage wherever an even temperature is needed, for example, in tobacco barns, hot houses and even in homes. 5 Our stove overcomes the greatest disadvantage of wood fuel which is its tendency to burn up quickly and erratically at an unpleasant and even dangerous temperature. In overcoming this disadvantage we provide a stove that requires very little attention and one which burns an economic fuel in an economic manner. 10

What we claim is:

1. A wood-burning brooder stove comprising an air tight fire chamber, a substantially air tight 15 door in the front of said chamber, and a hover connected to the upper edge of the stove, and extending completely around the stove, said hover having a section resting in part against the door to aid in keeping it air tight and being 20 movable to expose the door for refueling.

2. A wood-burning brooder stove comprising a combustion chamber in its upper portion, a side door for permitting the feeding of fuel into said chamber, a downwardly dished centrally apertured baffle in the upper part of the combustion chamber to protect the top of the stove from the direct radiant heat of the fire in the lower part of the combustion chamber thereby diminishing direct radiation and conduction of heat 25 upward into the brooder room, said baffle also serving to direct the hot combustion gases against the side walls of the stove, and a hover connected to the top rim of the stove for conserving the heat conducted thru the side walls, 30 a section of said hover being hinged at the top and normally resting against the door to assist in holding it closed. 35

3. The device of claim 1 in which the movable section is hinged at the top to the stove and has

a cut away portion for fitting over the closed door when the section is lowered to its normal position.

4. A wood-burning brooder stove having a fire chamber, a door in the front of said chamber, 5 said door reaching substantially to the top of said stove and a hover extending completely around the stove and supported from the top of the stove, a section of said hover being movable and hinged at the top and adapted to rest against 10 the door when lowered in cooperative position with the rest of the hover.

5. In a brooder of the type in which a hover is supported on the casing of a wood-burning 15 stove and means are provided beneath the hover for regulating the flow of air to maintain closely the desired brooding temperature while insuring a slow burning of the wood so that the brooder will operate for long periods without attention: 20 a casing, a sheet metal fire-pot dividing the casing into a fire chamber above and an air chamber below, said fire-pot having sloping walls providing an air space between the walls of the fire-pot and the casing, said sloping fire-pot walls 25 having a plurality of spaced louvred portions constituting indents from the sheet metal to provide air inlet openings on opposite ends of the fire-pot and forming the sole communication between the fire chamber and the air space between 30 the fire-pot and the lower portion of the casing, said louvres being located on the fire chamber side of the fire-pot so as to direct the flow of air through the openings downwardly into the fire-pot and also tending to keep fuel from blocking 35 said openings and thus restricting the flow of air.

PERRY S. MARTIN.
CHARLES C. TURNER.
